(57) **CLAIM**

The ornamental design for a clutch, as shown and described.

DESCRIPTION

FIG. 1 is a front perspective view of a clutch showing the new design in which the clutch is shown in a closed state; FIG. 2 is a left side view of the design of FIG. 1;

FIG. 3 is a right side view of the design of FIG. 1;

FIG. 4 is a front view of the design of FIG. 1;

FIG. 5 is rear view of the design of FIG. 1;

FIG. 6 is a top view of the design of FIG. 1;

FIG. 7 is a bottom view of the design of FIG. 1;

FIG. 8 is a front perspective view of the design of FIG. 1 in which the clutch is shown in a first open state; and,

FIG. 9 is a rear perspective view of the design of FIG. 1 in which the clutch is shown in a second open state.

The broken lines depict portions of the clutch that form no part of the claimed design.
